UNITED STATES PATENT OFFICE.

FELIX GREMMELS, OF MANNHEIM, GERMANY, ASSIGNOR TO TECHNO-SERVICE CORPORATION, OF NEW YORK, N. Y., A CORPORATION OF NEW YORK.

SHIP-LOCK LIFT.

1,392,638.

Specification of Letters Patent. Patented Oct. 4, 1921.

Application filed June 15, 1920. Serial No. 389,258.

To all whom it may concern:

Be it known that I, FELIX GREMMELS, a subject of the German Republic, and resident of Mannheim, in the German Republic, 5 have invented a certain new and Improved Ship-Lock Lift, of which the following is a specification.

Ship-lock lifts must in certain cases be erected upon a rather small place, for instance in a rocky valley, where, besides the canal, also other traffic routes pass through. 10 The ship-lock lift forming the subject-matter of this invention is particularly suited for such conditions. Another advantage of 15 it consists in its independency of changes in the height of the tail water lever, which can now easily be overcome.

The lift consists, generally, first, of two or more double-armed levers consisting in 20 their turn each of an iron structure or girder-work; second, of the tank which hangs on the lower ends of said levers; and third, of a counter-poise which is supported by the upper arms of the said levers. These 25 arms form each a kind of bracket carrying rails upon which the counter-poise may be moved along by means of a motor, preferably an electro-motor. The upper lever-arms or brackets, as well as the rails, are 30 curved upward in the direction to the ends of said lever-arms or brackets, their shape being such that the difference of weight resulting from whether the tank is still in the tail water, or already above it, is balanced 35 by the position of the counter-poise with respect to the more or less oblique position of the levers.

An important feature of my invention is that besides the tank also the counter-poise 40 is and remains always in horizontal position.

In order to make my invention more clear, I refer to the accompanying drawing, in 45 which similar letters denote similar parts throughout the several views, and in which:

Figure 1 shows, by way of example, a diagrammatical representation of a ship-lock lift constructed according to my invention; the levers, the tank and the counter-poise 50 being shown in their two main positions, viz., the tank being in line with the tail water (full lines) as well as in line with the head water (dotted lines).

Fig. 2 is a plan of the ship-lock lift, the

parts being represented in that position 55 which corresponds to the full lines of Fig. 1.

In the example shown, there are four masonry scales *a*, each of which supports a double-armed lever *d*, *d*¹ by mediation of a 60 roller-bearing *c*. These four bearings are in the same horizontal plane. Each lever consists of an iron structure or girder-work forming practically a straight arm *d* extending in the direction to the tank, and a 65 curved or angular arm *d*¹ (the before-mentioned bracket) which extends practically in the opposite direction.

The arms *d* of each pair of the levers at the head-water end, as well as at the tail-water end, converge, and the arms *d*¹ diverge (Fig. 2), and the distance between the arms *d*¹ transversely to the canal is such that the arms *d* of the levers at the tail-water end may pass through between the 75 arms *d*¹ of the levers at the head-water end, as may also the neighboring part of the tank.

The tank is suspended in bearings *e* of the lever-arms *d*. The distance between the 80 bearings *e*, *e* in the longitudinal direction of the tank corresponds exactly to the distance between the bearings *c*, *c*. The distance between the bearing *c* and the bearing *e* of a lever *d*, *d*¹ is exactly the same 85 with all levers, and it is thus obvious that the tank *b* remains in horizontal position at every degree of inclination of the levers *d*, *d*¹.

The bracket-like arms *d*¹ of the levers 90 carry upon their upper surfaces rails supporting a big counter-poise *g* having wheels *r*. The rails are upwardly curved in the direction to the ends of the lever-arms *d*¹ (Fig. 1). The distance between the wheels 95 *r*, in the longitudinal direction of the canal, corresponds to the distance between the bearings *c*, *c* in the same direction, and as the lever-arms *d*¹ are of equal size and shape, the poise *g* remains always in horizontal position.

The object of the poise *g* is to counter-balance the tank *b* with its contents in every position. When it dips into the tail-water, or is lifted out of it, the weight acting at 105 the lever-arms *d* changes considerably, and it becomes necessary to counter-balance the difference. This is effected by displacing

the poise g upon the rails f of the lever-arms d^1 .

The poise g is provided with an electro-motor m , by means of which at least one of the wheels r is rotated by the mediation of geared transmission wheels (Fig. 1). The poise may thus be moved forward and backward upon the rails f whereby the active length of the lever-arms d^1 is changed. 10 Supposing, the tank, the levers, and the poise, be in the position shown in full lines in Fig. 1 and the poise be moved from the left to the right, as indicated by the arrow, then the length of the active parts of the 15 lever-arms d^1 increases in proportion to the length of way covered by the poise, as does also the effect of the latter in proportion to the weight of the tank with its contents, which is slowly lifted from the tail water 20 to the head water until it arrives in the position shown in dotted lines in Fig. 1. Means may be provided for preventing switching in the current if the sluices at the head-water and at the tail water are not 25 completely closed.

The shape of the ends of the lever-arms d^1 is such that the counter-poise cannot leave the rails f . Safety-abutments may be provided to break the electric current automatically when the wheels r arrive at the one or the other end of their path.

I wish it to be understood, that I do not limit myself to the employment of only two pairs of levers, such as d , d^1 or similar ones, 30 but three or more pairs, also arranged one after the other, may be employed according to the length of the tank to be lifted in the manner described.

Having now described my invention, what

I desire to secure by a patent of the United States is:

1. In a ship-lock-lift, the combination of pairs of similarly shaped double-armed levers, of which one pair is located adjacent the tail water end of a canal and the other adjacent the head water end of the same; of supports for said levers; a tank suspended from the corresponding arms of all of said levers; rails provided upon the other arms of said levers; a counter-poise carried by said other lever-arms and being adapted to be displaced along said rails in horizontal direction; and means for thus displacing said counter-poise.

2. In a ship-lock lift, in combination: 55 pairs of double-armed levers, of which one pair is located at the sides of the tail water end of the canal and the other at the head-water end of the same; supports for said levers; a tank suspended from corresponding pairs of arms of the said levers, the respective lever-arms from which said tank is suspended being converging and the other lever-arms being diverging in such a measure that the converging arms of the tail- 65 water lever-pair may, together with the tank, pass through the space between the diverging arms of the other lever-pair; a counter-poise arranged upon the diverging arms of said lever-arms and adapted to be 70 displaced along the same; and means for thus displacing said counter-poise.

In testimony whereof I affix my signature in presence of two witnesses.

FELIX GREMMELS.
